UNITED STATES PATENT OFFICE.

JOSEPH FAVATA, JR., OF BUFFALO, NEW YORK.

FASTENER FOR BARBERS' HAIR CLOTHS AND THE LIKE.

Application filed July 21, 1923. Serial No. 652,926.

To all whom it may concern:

Be it known that I, JOSEPH FAVATA, Jr., a citizen of the United States, residing at Buffalo, in the county of Erie and State of New York, have invented certain new and useful Improvements in Fasteners for Barbers' Hair Cloths and the like, of which the following is a specification.

My invention relates to improvements in fasteners for barbers' hair cloths and the like; its primary object being to provide a simple and convenient device for such purpose which is at all times retained on the hair cloth and whereby said cloth can be conveniently fastened around the neck of a person having his hair cut.

Another object of my invention is to provide a device of this kind which can be stamped out of a single piece of flexible material capable of being bent into the desired form and retained in such form and wherein the inherent resiliency of the material from which it is constructed is depended upon to retain the overlapping portions of a hair cloth in position around the neck of a person having his hair cut.

A further object of my invention is to provide a device of this kind which has a comparatively flat inner or neck-bearing surface so that abrasion of the skin is avoided and so that a comfortable feeling is given the person to whom the device is applied.

With the above and other objects in view, the invention consists in the novel features of construction and in the arrangement and combination of parts to be hereinafter described and more particularly pointed out in the subjoined claims.

In the drawings:—

Fig. 1 is a view showing the manner in which the fastener is used on a person having a hair cloth placed around him preparatory to cutting the hair.

Fig. 2 is a perspective view of the blank from which the fastener is constructed.

Fig. 3 is an elevation of the fastener in completed form.

Fig. 4 is an enlarged longitudinal section taken on line 4—4, Fig. 3.

Fig. 5 is an enlarged transverse section taken on line 5—5, Fig. 3.

Fig. 6 is an enlarged transverse section taken on line 6—6, Fig. 3.

Fig. 7 is a perspective view of a modified construction of the device viewed from the inner side.

Fig. 8 is a perspective view of said modified construction view from the outer side.

Fig. 9 is a transverse section taken on a plane passing through the outer retainer flap of said modified construction.

The device is formed of resilient material, and in preferred form is constructed of a blank, such as shown in Fig. 2 in which an elongated portion 10 is provided having ears or flaps 11, 12 extending laterally therefrom at opposite ends and at one edge thereof. Each of said ears has inwardly-diverging incisions 13 formed therein, starting from a common point 14, and the material between said incisions is adapted to be bent at right angles to the blank to form penetrating points, as will appear hereinafter.

The blank is adapted to be bent or curved upon itself along the dotted lines 15, 16, 17 and 18. It is first bent or curved upon itself transversely along the lines 16, 17 so that a body portion in the form of an elongated loop 19 is provided having opposite end portions of the blanks lying in contact as at 20, and forming one longitudinal side of the loop. In other words, the loop is provided with a double side 21 and a single side 22 connected by the curved ends 23. After thus forming the device, the ears 11, 12 are bent or curved over the body portion along the dotted lines 15, 18 in Fig. 2, the ear 11 being bent over both the double and single sides of the loop or body portion and thence downwardly, as shown in Fig. 5, while the other ear 12 is bent downwardly in an opposite direction over the double side, as shown in Fig. 6, the bent or curved portion of the ear 11 being considerably larger than that of the ear 12.

The blank 10 is provided with three perforations 24, 25, 26, and the material between the diverging incisions are bent at right angles to the ears or flaps, as stated, to form inwardly-projecting pointed prongs or pins 27, 28, respectively. When the ear 11 is bent downwardly, the prong or pin 27 thereof will be brought into alinement with the opening 25 formed in the body portion of the blank, which will, when the blank is bent into shape, be arranged in the single side of the loop near one end thereof. The

- openings 24 and 26 are in registration, and when bending the ear or flap 12 downwardly, the prong 28 thereof will be brought into alignment with said openings 24 and 26; the 5 prong 27 extending into the loop through the opening 25 in the single side of said loop and the prong 28 extending into the loop through the registering openings 24 and 26 in the double side of said loop.
- 10 The inherent resiliency of the ears or flaps will tend to maintain the same in contact with the body portion of the device; thus the prongs or pins thereof are at all times entered in the elongated loop of said body 15 portion and are prevented from coming in contact with the person having the hair cloth applied thereto, since the pointed extremities of said prongs or pins terminate within the elongated loop of said device.
- 20 When applying the device to a hair cloth, the ear or flap 12 which extends downwardly transversely of the double side of the loop, as best shown in Fig. 7, is drawn outwardly, as shown by dotted lines in said figure, to 25 enable one end of the hair cloth to be slipped between said double side and said ear or flap, the prong or pin 28 of said ear or flap being drawn from the registering openings in the overlapping parts of said body portion so as to enable the hair cloth to be 30 slipped upwardly in contact with said body portion. When the hair cloth is properly positioned, said ear or flap 12 can be released and the inherent resiliency of the 35 same will cause it to immediately return under pressure against the hair cloth, with the result that the prong or pin 28 of said ear or flap will penetrate the hair cloth and act to properly attach the device to said 40 hair cloth.
- The device is at all times retained on the hair cloth so that it is simply necessary to place the hair cloth around a person and lift up the ear or flap 11 so that the opposite 45 end of the cloth may be slipped between the flap and the body portion of the device and when so positioned, the flap 11, after being drawn outwardly with the fingers to the position shown with dotted lines in Fig. 5, 50 will immediately return to its normal position, with the result that the prong or pin 27 thereof will penetrate the hair cloth and retain the latter in proper position around the person whose hair is to be cut, the cloth 55 being drawn tightly around the neck to prevent the hair cut from the person from falling between the hair cloth and the neck or body of the person.
- In order to remove the hair cloth from 60 the person, it is simply necessary to lift up the ear or flap 11 until the prong or pin 27 thereof is withdrawn from the hair cloth. This will allow one end of the cloth to be drawn downwardly out of the device and be swung around to the front of the per-

son so that the entire cloth can be conveniently removed while retaining the device in secure position at the other end of the hair cloth.

It will be noticed that by the use of the 70 elongated loop construction shown in Fig. 4, the prongs or pins are fully protected. In other words, the prong or pin 28 projecting through the single side of the elongated loop has the double side of said loop acting 75 as a guard for the same, while the prong or pin 27 passed through the double side of the loop has the single side of the loop acting as a guard for the same. In this manner the person on whom the hair cloth is 80 to be applied cannot possibly be injured by the prongs, and since the inner side of the loop is substantially flat to conform to the neck, it will be quite comfortable when bearing against the neck.

In the modification shown in Figs. 7 to 10, the body portion, designated by the numeral 29, is formed of a single length of material, and at the upper edge thereof it has two ears or flaps 30 31 bent outward and downwardly therefrom, one of said ears being at each end of the body portion. Each of the ears, in this modified construction, is provided with a pin or prong, which is adapted to engage the hair cloth in the same 95 manner as described with reference to the preferred construction shown in Figs. 1 to 6; and if desired the body portion may have an indentation 32 formed therein in line with one of the prongs, or such indentations may be formed in line with both prongs of said ears or flaps, the pointed ends of said prongs or pins being entered in the indentations; one of said ears being adapted to engage one end of the hair cloth and by 100 the use of said ear its prong be retained thereon, while the other ear is adapted to engage the other end of the hair cloth, as and in the manner described with reference to the two ears or flaps shown in the preferred construction.

The indentation 32 or each of them if two are used, is necessarily formed on one side of the body portion 29, and consequently at the opposite side of said body portion the metal thereof is stamped outwardly to form a teat, which may be objectionable when coming in contact with the neck. However, as there are other uses for a device of this kind, such for instance as fastening the 115 ends of an apron together when placed around the body, the modified construction shown in Figs. 7 to 10 would serve for this purpose fully as well as the preferred construction shown in Figs. 1 to 6.

Having thus described my invention, what I claim is:

1. A fastener of the kind described, comprising a body portion and two resilient flaps extending from one edge of said body 120

portion, said flaps being directed transversely and having prongs extending inwardly at a right angle therefrom.

2. A fastener of the kind described, comprising an elongated body portion having resilient retainer flaps at opposite ends, said flaps being arranged at the upper edge of said body portion and being directed downwardly therefrom at opposite sides of 10 said body portion, each of said flaps having a retainer prong thereon.

3. A fastener of the kind described, comprising an elongated body portion formed of sheet material bent into the form of an 15 elongated loop and having retainer flaps extending from one side of said loop, one of said flaps being directed outwardly and downwardly from said side and the other being directed inwardly and downwardly 20 over the other side of said loop.

4. A fastener of the kind described formed of an elongated blank having flaps at opposite ends extending from one edge thereof, said blank being bent between its 25 ends into loop formation, opposite end portions of said blank being overlapped and lying in contact with each other, said flaps being bent downwardly and lying at opposite sides of said loop.

5. A fastener of the kind described 30 formed of a blank bent upon itself between its ends and having the end portions thereof

overlapped and in contact, thus forming an elongated loop, one wall of said loop having retainer flaps extending therefrom, one of 35 said flaps being bent outwardly and downwardly across said side and the other being bent over both sides of said loop and downwardly along the other side thereof.

6. A fastener of the kind described, comprising an elongated body portion of loop formation and resilient flaps at opposite sides of said body portion arranged transversely to normally bear against said body portion, said body portion having openings 45 and said flaps having prongs projecting through said openings into said body portion.

7. A fastener of the kind described formed of an elongated piece of material 50 bent upon itself between its ends to form an elongated loop with one side thereof formed by the ends of said material overlapping, said overlapping portions having registered 55 openings therein, an opening at the opposite side of said loop, and resilient flaps extending from the edge of the material at one side of the loop and being curved and directed downwardly at opposite sides of 60 the loop, said flaps having prongs extending through the openings of said body portion.

In testimony whereof I affix my signature.
JOSEPH FAVATA, JR.
